Kevin Prince(57) **CLAIM**

The ornamental design for a twisted double wall glass, as shown and described.

DESCRIPTION

FIG. 1 is a perspective view of a twisted double wall glass, showing my new design;

FIG. 2 is a front elevational view of FIG. 1, the rear elevational view being a mirror image thereof;

FIG. 3 is a top plan view of FIG. 1;

FIG. 4 is a bottom plan view of FIG. 1; and

FIG. 5 is a cross-sectional view of FIG. 1, taken along cut-line 5-5 in FIG. 3;

FIG. 6 is a perspective view of a second embodiment thereof;

FIG. 7 is a front elevational view of FIG. 6, the rear elevational view being a mirror image thereof;

FIG. 8 is a top plan view of FIG. 6;

FIG. 9 is a bottom plan view of FIG. 6; and,

FIG. 10 is a cross-sectional view of FIG. 6.
